UNITED STATES PATENT OFFICE

2,163,882

CONCRETE PLACING APPARATUS

Corwill Jackson, Ludington, Mich.

Application January 22, 1936, Serial No. 60,237

10 Claims. (Cl. 94—48)

This invention relates to improvements in concrete placing apparatus.

The main objects of this invention are:

First, to provide a machine for the placement of concrete such as concrete slabs, pavements, the walls of ditches or conduits and the like which is of very large capacity and is highly efficient in the rapid and effective placing of concrete masses particularly those of large aggregate and low water content.

Second, to provide a machine of this character which is of wide adaptability and may be used by comparatively unskilled labor.

Third, to provide a machine of this character which is simple and economical in structure and at the same time strong and durable.

Objects relating to details and economies of the invention will appear from the description to follow. The invention is defined and pointed out in the claims.

A preferred embodiment of the invention is illustrated in the accompanying drawings, in which:

Fig. 1 is a side elevation of a machine embodying the features of my invention illustrated in operative relation to a tractor and finishing screed, the various parts being conventionally shown for convenience in illustration.

Fig. 2 is a fragmentary plan view with parts sectioned and broken away for convenience in illustration.

Fig. 3 is an enlarged fragmentary view partially in section on line 3—3 of Figs. 2 and 6.

Fig. 4 is an enlarged fragmentary end view, the parts being shown in one position by full lines and in another position by dotted lines.

Fig. 5 is an enlarged detail view partially in section on line 5—5 of Figs. 2 and 4.

Fig. 6 is a vertical section on line 6—6 of Figs. 2 and 3.

Fig. 7 is a section through the vibratory member on line 7—7 of Figs. 2 and 5.

Fig. 8 is a section through the vibratory member on line 8—8 of Fig. 3.

Fig. 9 is a fragmentary front elevation or elevation looking from the right of Fig. 10 of a modified form or embodiment of my invention.

Fig. 10 is a vertical section of the parts shown in Fig. 9 on line 10—10 thereof.

In the accompanying drawings, 1 represents one of the forms of the concrete pavement or slab, these forms being adapted as a track for the concrete placing machine and also for its propelling tractor designated generally by the numeral 2.

My concrete placing or working machine in the embodiment illustrated comprises a frame 3 having depending standards 4 at the ends thereof, carrying wheels 5 being mounted by the supporting arms or bars 6 pivoted at 7 on these standards so that by raising and lowering the ends 8 of the arms, the frame 3 and its standards 4 are raised and lowered.

The means for adjusting and supporting the arms 8 in their adjusted positions, in the embodiment illustrated, comprises cables 9 connected to the ends 8 of the arms and passed over suitable guiding pulleys 10 and 11 on the frame 3 to the cable extension 12 which is in turn connected to a drum 13 provided with a ratchet wheel 14, the drum being actuated or adjusted by the ratchet lever 15. With this arrangement, the arms are swung on their pivots to raise or lower the frame and this raises or lowers the vibratory or screed element 16.

This vibratory element is, in the embodiment illustrated, of tubular cylindrical form and is provided with an upwardly projecting longitudinal top plate 17 and with forwardly diverging end wings 18 designed to draw the material to be treated into the vibratory member and prevent its flowing around the ends of the same. This vibratory member is supported to permit vibratory movement, the supporting means preferably being such as to permit vibratory movement in an orbital path.

In the mounting best shown in Fig. 5, the vibratory member is mounted at its ends upon the standards 4, the standards being provided with inwardly projecting journal-like studs 19 carrying the resilient disk cushioning members 20. These cushioning members are arranged in holders 21 provided therefor at the ends of the vibratory member, the studs being flanged at 22, the disk being retained between this flange and the collar 23 on the studs. The holders are seated within and fixedly secured to the ends of the vibratory members. This provides supports for the vibratory member which permits its being vibrated at high frequency and supports it so that it may be urged against a mass of concrete to be placed.

The means for vibrating the vibratory member in the embodiments illustrated comprises a shaft or rotor 24 disposed longitudinally within the tubular vibratory member and supported therein by means of spaced bearings 25 fitting within the walls of the vibratory member. The shaft is preferably a sectional shaft for convenience in assembling. The shaft is provided

with unbalancing weights 26 so that when the shaft is rotated, vibratory impulses are imparted to the vibratory member. The rotor is driven from an engine or motor 27 mounted on the 5 carriage 3.

A boot or transmission housing 28 is mounted on the vibratory member and is supported in upright position by means of cushioned brackets 29—see Fig. 2. A driving shaft 30 is supported 10 at one end in the bearing 31 carried by this housing and by a bearing 32 on the carriage frame, a resilient flexible vibration absorbing section 33 being provided between the bearings so that the vibrations of the vibratory member are 15 not imparted to the frame or to the engine.

On the end of the shaft 30 I mount a pulley 34 having a double groove for the V-belts 35, the shaft or rotor 24 having a suitable pulley 36 co-acting with these belts. A belt tightening pulley 20 37 is provided for the belts 35, this belt tightening pulley taking the whip or minimizing the whip of the belts which might result from the vibration.

The bearing members 25 are secured in position within the vibratory member by means of the set 25 screws 38 which have tapered tips 39 engaging bores 40 provided therefor in the members 25.

Where it is desired to further smooth the surface of the concrete, I provide a screed 41 which may be pushed along on the forms 1 by means of 30 the abutment 42—see Fig. 1. The vibrator carriage is provided with a push bar 43 adapted for attachment at 44 to the tractor 2.

In the embodiment of my invention shown in Figs. 9 and 10, the frame 50 corresponding to the 35 frame 3 of the previously described embodiments is provided with standards 51 on which the wheel supporting arms 52 are mounted, the carrying wheels 53 being mounted on these arms and designed to travel on the forms 1 which constitute tracks or rails. The supporting arms 52 are adjusted through cables 5. The vibratory member 54 is preferably cylindrical and provided with an upwardly projecting longitudinal web or top plate 17.

45 The vibrating means is preferably that illustrated in the previously described embodiments, housed within the vibratory member, comprising a rotor or shaft 24 having an unbalancing weight 26 thereon. The vibratory member is resiliently 50 suspended by means of the strap hangers 55 arranged in opposed upwardly diverging pairs at the ends of the vibratory member, the vibratory member being provided with upwardly projecting ears 56 having holes 57 therein receiving the 55 hangers.

The frame is provided with ears 58 receiving the upper ends of the straps. By arranging these hanger straps in downwardly diverging pairs, they tend to centralize or support the vibratory 60 member in a central position while permitting free orbital vibration thereof. To propel the vibratory member against and over the mass of concrete being treated, the frame is provided with depending arms 59 having resilient buffers 60 65 engaging the vibratory member as shown in Fig. 10.

70 The flexible hangers are preferably attached to the vibratory member above the longitudinal center thereof or the axis of the shaft carrying the unbalancing weights 26. This flexible means of suspension is found to effectively eliminate any nodes or dead spots in the vibratory member. Assuming that the vibratory member is twenty 75 feet long, the hangers are preferably arranged

about five feet from the ends of the vibratory member.

The embodiment of Figs. 9 and 10 has some advantage over that shown in previously described embodiments particularly in that the vibratory member has a somewhat greater amplitude of movement and, as stated, there are no nodes or dead spots and is uniformly vibrated throughout its length. It is preferably provided at its ends with the wings 62.

In the commercial embodiment which I have found very practical, the vibratory screed member is six inches in diameter and twenty feet in length. Its length of course would be varied according to the spacing of the forms and this is 15 governed by the pavement or slabs to be laid.

In both forms of mounting illustrated, the vibratory member is resiliently or flexibly supported to permit effective vibration thereof.

The machine is especially designed by me for 20 the practice of my Patent No. 1,787,449, dated January 6, 1931. It is, however, adapted for placing concrete varying widely in moisture contents and in aggregate. The structure is quite economical but at the same time the machine 25 is of large capacity and capable of many uses—that is, it may be used in placing concrete pavements, bridge decks, in walls for water conduits or canals and the like.

I have illustrated and described my improvements in an embodiment which I have found 30 very practical. I have not attempted to illustrate or describe other embodiments or adaptations as it is believed this disclosure will enable those skilled in the art to embody or adapt my 35 improvements as may be desired.

Having thus described my invention, what I claim as new and desire to secure by Letters Patent, is:

1. In a machine of the class described, the combination of a carrying frame provided with depending standards, carrying wheels, supporting arms for said carrying wheels pivotally mounted on said standards, a cylindrical vibratory element disposed horizontally between said standards and 45 provided with a vertically disposed top plate and with forwardly projecting wings at its ends, means for mounting said vibratory element to permit vibratory movement thereof, a shaft disposed longitudinally within said vibratory member and provided with unbalancing weights, a centrally disposed transmission housing projecting upwardly from said vibratory element and opening thereto, cushioned means for supporting said housing in upright position, a motor mounted 50 on said carrying frame and provided with a driving shaft supported at one end by said housing and having a flexible vibration absorbing section between the housing and the motor, driving connections for said driving shaft to said vibratory shaft arranged in said housing, and means for 55 adjustably supporting said wheel supporting arms.

2. In a machine of the class described, the combination of a carrying frame provided with 60 depending standards, carrying wheels, supporting arms for said carrying wheels pivotally mounted on said standards, a tubular vibratory element disposed horizontally between said standards, means for mounting said vibratory element to 65 permit vibratory movement thereof, a shaft disposed longitudinally within said vibratory member and provided with unbalancing weights, a centrally disposed transmission housing projecting 70 upwardly from said vibratory element and 75

opening thereto, cushioned means for supporting said housing in upright position, a motor mounted on said carrying frame and provided with a driving shaft supported at one end by said housing 5 and having a flexible vibration absorbing section between the housing and the motor, driving connections for said driving shaft to said vibrating shaft arranged in said housing, and means for adjustably supporting said wheel supporting 10 arms.

3. In a machine of the class described, the combination of a carrying frame provided with depending standards, carrying wheels, supporting arms for said carrying wheels pivotally mounted 15 on said standards, a tubular vibratory element disposed horizontally between said standards, means for mounting said vibratory element to permit vibratory movement thereof, a shaft disposed longitudinally within said vibratory member and provided with unbalancing weights, a centrally disposed transmission housing projecting upwardly from said vibratory element and opening thereto, cushioned means for supporting 20 said housing in upright position, a motor mounted on said carrying frame and provided with a driving shaft supported at one end by said housing and having a flexible vibration absorbing section between the housing and the motor, driving connections for said driving shaft to said vibrating 25 shaft arranged in said housing, and means for adjustably supporting said wheel supporting arms including an adjusting lever and cables connecting said lever to said wheel supporting arms, said cables being provided with guide pulleys 30 whereby the arms are simultaneously adjusted for raising and lowering said vibratory element.

4. In a machine of the class described, the combination of a carrying frame provided with depending standards, carrying wheels, supporting 40 arms for said carrying wheels pivotally mounted on said standards, a tubular vibratory element disposed horizontally between said standards and provided with a vertically disposed top plate and with forwardly projecting wings at its 45 ends, means for mounting said vibratory element on said frame to permit vibratory movement thereof, a vibrating means for said vibratory element comprising a shaft disposed longitudinally within said vibratory member and provided with unbalancing weights, and means for adjustably 50 supporting said wheel supporting arms.

5. In a machine of the class described, the combination of a carrying frame provided with depending standards, carrying wheels, supporting 55 arms for said carrying wheels pivotally mounted on said standards, a tubular vibratory element disposed horizontally between said standards, means for mounting said vibratory element on said carrying frame to permit vibratory movement thereof, a vibrating means for said vibratory element comprising a shaft disposed longitudinally within said vibratory member and provided with unbalancing weights, and means for adjustably supporting said wheel supporting arms.

tudinally within said vibratory member and provided with unbalancing weights, and means for adjustably supporting said wheel supporting arms whereby said frame and said vibratory element may be vertically adjusted.

6. In a machine of the class described, the combination of a carrying frame provided with depending standards, carrying wheels, supporting arms for said carrying wheels pivotally mounted on said standards, a tubular vibratory element disposed horizontally between said standards, means for mounting said vibratory element to permit vibratory movement thereof, a vibrating means for said vibratory element comprising a shaft disposed longitudinally within said vibratory member and provided with unbalancing weights, and means for adjustably supporting said wheel supporting arms including an adjusting lever and cables connecting said lever to said wheel supporting arms, said cables being provided with guide pulleys whereby the arms are simultaneously adjusted for raising and lowering said vibratory element.

7. In a machine of the class described, the combination of a wheeled carriage mounted for vertical adjustment on its wheels, a horizontally disposed vibratory element disposed transversely of the path of travel of the carriage and mounted on said carriage for vertical adjustment therewith and to permit vibratory movement in an orbital path, and means for vibrating said vibratory element carried thereby.

8. In a machine of the class described, the combination with a carrying frame, of an elongated cylindrical tubular horizontally disposed vibratory element, pairs of flexible non-extensible hanger straps on said frame secured to said vibratory element, means for vibrating said vibratory element including an unbalanced rotor within said vibratory element, and a thrust member 40 for said vibratory element.

9. In a machine of the class described, the combination with a carrying frame, of an elongated cylindrical tubular horizontally disposed vibratory element, pairs of downwardly converging 45 flexible non-extensible hanger straps on said frame secured to said vibratory element in a plane substantially above its axis, means for vibrating said vibratory element including an unbalanced rotor within said vibratory element, and a cushioned thrust member engaging said vibratory element.

10. In a machine of the class described, the combination with a carrying frame, of an elongated horizontally disposed vibratory element, 55 pairs of downwardly converging flexible non-extensible hanger straps on said frame secured to said vibratory element, means for vibrating said vibratory element, and a thrust member engaging said vibratory element.

CORWILL JACKSON.
